UNITED STATES PATENT OFFICE

2,507,362

VENT CONTROLLED LIQUID MEASURING
MEANS

Bernhard Wilhelm, Waterbury, Conn.

Application August 13, 1945, Serial No. 610,419

4 Claims. (Cl. 222—457)

1

This invention relates to liquid dispensing apparatus, and more particularly to an improved bottle stopper dispenser having means to deliver a measured quantity of liquid when the bottle or other container is tipped to a horizontal position.

One object of this invention is to provide a device of the above nature having a dome-shaped chamber which is provided with a horizontal open vent tube in one side.

A further object is to provide a device of the above nature having a control tube adjustably fitted into the shank of the stopper to regulate the speed of flow of the liquid passing from the bottle into the dome at each dispensing operation, and thus controlling the amount of air trapped in said dome and container.

A further object is to provide a device of the above nature, having a side spout located opposite the air vent tube and having a hinged cover carrying a depending weighted stem for engaging the bottom of said spout to limit the amount of opening of said cover.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a side sectional view of a bottle having the improved stopper dispenser installed therein—the bottle being shown in vertical position.

Fig. 2 is a similar view of the same, with the bottle shown in horizontal position, and with the hinged cover shown in open position.

Fig. 3 is a top plan view of the dispenser shown by itself.

Fig. 4 is a perspective view of the control tube shown by itself.

Referring now to the drawing in which like reference numerals denote corresponding parts throughout the several views, the numeral 10 indicates a bottle having a reduced neck 11 which is adapted to receive the stopper dispenser forming the subject of the present invention.

The improved stopper dispenser comprises a rigid double-walled shank 12 constructed of metal or plastic, and which is adapted to be surrounded by a tubular cork sealing band 13, as clearly shown in Figs. 1 and 2. The shank 12 is provided with a central cylindrical aperture 14 open at the

2

top and bottom, and an outer annular channel 15 closed at the top and open at the bottom. The shank 12 is integrally connected at its top to a dome-shaped chamber 17 into one side of which extends a horizontal open vent tube 18 communicating with the outer atmosphere. The channel 15 is connected by an inclined passage 16 to a side spout 19, said passage 16 being located directly opposite from the air vent tube 18, and serving to conduct liquid from the bottle 10 into the spout 19 and thence to a suitable receptacle (not shown).

The spout 19 is closed at the top by a flat cover 20 having a rear curled eye 21 embracing a hinge pin 22 which is secured to a pair of eyes 22a on a lug 23 projecting outwardly from the side of the dome 17 at a point directly opposite from the vent tube 18. The cover 20 is provided with a depending rigid stem 24 having at its lower end a cylindrical weight 25 to cause said cover to close automatically when in the vertical position shown in Fig. 1. The weight 25 is adapted to engage the bottom of the spout 19 for limiting the amount of opening of the hinged cover 20 when the bottle 10 is swung to the horizontal dispensing position shown in Fig. 2.

In order to control the amount of air which will be entrapped within the dome and bottle at each dispensing operation, provision is made of a control tube 26 which is fitted detachably into the bottom of the central aperture 14 of the shank 12, and is provided at its lower end with a solid enlarged knurled head 27. The control tube 26 has an open top 28 and a pair of spaced vertical side slots 29, 29, leaving a vertical front strip 30 and a vertical rear strip 31.

The strip 30 is provided with a narrow slot 32, one side of which has a graduated scale 33 to facilitate the adjustment of the control tube 26 accurately with respect to the shank 12.

The control tube 26 is adapted to be accurately held in adjusted position by a horizontal set screw 34, passing through both walls of the shank 12, and having a reduced end 34a located in the slot 32, said set screw having a kerfed head 35 to receive a screw driver, for convenience in manipulation.

Operation

In use, when the bottle 10 is tipped from the vertical position (shown in Fig. 1) to the pouring position, which may be horizontal, as shown in Fig. 2, or tilted even further, a part of the liquid will flow directly through the spout 19 and a further part will pass through the control tube

26 and the central aperture 14 of the double wall shank 12 into the lower part of the dome 17. During this initial period, air to replace the liquid flowing out of the spout will enter the dome through the vent 18 and pass upwardly into the bottle 10. This will continue until the liquid in the dome 17 reaches or passes above the level as shown in Fig. 2, thus sealing the vent tube against the intake or further air from the atmosphere and thus stopping the further dispensing of the liquid from the bottle. The adjustment of the control tube 26 will determine the amount of air which will thus be entrapped in the dome chamber and container, and this will regulate the amount of liquid dispensed, with a fair degree of accuracy, irrespective of the temperature and the amount of liquid remaining in the bottle. It will be understood that the greater the protrusion of the control tube 26 out of the shank 12, the more rapid will be the flow of liquid from the bottle into the dome, thus sealing off the vent tube 18 more quickly and reducing the amount of liquid dispensed at each operation.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a liquid dispenser adapted to be detachably secured in the mouth of a bottle or other container, a double-walled hollow stopper shank, a hollow dome chamber connected to the top of said shank, said chamber having on one side a horizontal interior air vent tube leading to the atmosphere, a spout connected to the outer channel of said shank and located directly opposite said vent tube, said hollow shank having a control tube detachably secured within the central aperture thereof, and means to adjust the longitudinal position of said control tube within said aperture.

2. In a liquid dispenser adapted to be detachably secured in the mouth of a bottle or other container, a double-walled hollow stopper shank, a hollow dome chamber connected to the top of

said shank, said chamber having on one side an interior air vent tube leading to the atmosphere, a spout connected to the outer channel of said shank and located opposite said vent tube, said double-walled shank having secured thereto a control tube having apertures to permit the free flow of liquid and air therethrough and a set screw passing through both walls of said shank and through said control tube for holding said control tube in adjusted position.

3. In a liquid dispenser adapted to be detachably secured in the mouth of a bottle or other container, a double-walled hollow stopper shank, a hollow dome chamber connected to the top of said shank, said chamber having on one side an interior air vent tube leading to the atmosphere, a spout connected to the outer channel of said shank and located opposite said vent tube, and an apertured control tube fitted into the central aperture of said shank, said control tube having an elongated slot provided with a graduated scale for permitting the accurate adjustment of said control tube with respect to said shank.

4. In a liquid dispenser adapted to be detachably secured in the mouth of a bottle or other container, a double-walled hollow stopper shank, a hollow dome chamber connected to the top of said shank, said chamber having on one side an interior air vent tube leading to the atmosphere, a spout connected to the outer channel of said shank and located opposite said vent tube, the cover of said spout being provided with a weighted depending stem adapted to engage with the lower wall of said spout when said bottle has been tipped to a horizontal position, and thus limit the amount of opening of said cover.
